UNITED STATES PATENT OFFICE.

HOWARD E. COFFIN, OF DETROIT, MICHIGAN.

CONTROL MECHANISM.

No. 920,916.

Specification of Letters Patent. Patented May 11, 1909.

Application filed April 13, 1908. Serial No. 426,757.

To all whom it may concern:

Be it known that I, HOWARD E. COFFIN, a citizen of the United States of America, residing at Detroit, in the county of Wayne and 5 State of Michigan, have invented certain new and useful Improvements in Control Mechanism, of which the following is a specification, reference being had thereto to the accompanying drawings.

10 The invention relates to control mechanism for motor vehicles and more particularly to the means for controlling the main clutch which couples the motor to the drive shaft.

15 The invention consists in the novel construction as hereinafter set forth.

In the drawings—Figure 1 is a side elevation of the control mechanism; Fig. 2 is a plan view thereof.

20 A is the motor vehicle frame. B is a rock shaft extending transversely of said frame and having secured thereto the depending rock arm C which operates the shiftable member D of the main clutch E.

25 F is a pedal lever mounted upon the rock shaft B and extending upward through an aperture in the foot board G of the vehicle body in convenient position for operation. H is another transversely extending rock shaft mounted upon the frame A parallel to 30 and in rear of the shaft B.

I is a hand controlled lever secured to the shaft H.

J is a depending rock arm on the shaft H and K is a rod or slide longitudinally adjustably secured in bearings L upon the frame A. This slide K has a forked upward extension K' for engaging a pin upon the rock arm J whereby the movement of said arm is communicated to the slide. The opposite end of 40 the slide K is fashioned to form an incline or cam K².

M is a rock shaft axially aligned with the rock shaft B and both of these shafts are tubular and mounted upon an inner rock

45 shaft N.

O is a rock arm on the shaft M which extends adjacent to the slide K and has an anti-friction roll P which lies in the path of the incline or cam K² on said slide.

50 Q is a rock arm on the shaft M located adjacent to the pedal F and having at its inner end a threaded bearing in which is secured the adjustable screw R, and this screw bears against the pedal F.

55 The construction above described is one in

which the clutch E may be controlled alternatively by the pedal F and the hand lever I, and the arrangement is such that the operation of the hand lever will also operate the pedal lever, but the operation of the pedal lever is independent of the hand lever and will not disturb the adjustment of the latter. This independent movement of the pedal lever is permitted by reason of the fact that the rock arm Q is free to move with the rock 60 shaft M, arm Q and pedal lever F, and is not positively coupled with the rod or slide K, but is free to move independently thereof whenever the pedal lever F is directly actuated. On the other hand the movement of 65 the slide under the actuation of the lever I will always positively actuate the rock arm Q and through the medium of the rock shaft M and rock arm Q they impart movement to 70 the pedal.

The continued use of the clutch E will result in wearing of the friction surface which necessitates a slightly greater movement of the shiftable member D to effect the locking 80 of the clutch. This would change the position to which the lever I must be adjusted in operating the clutch, and to avoid such a result the screw R may be adjusted to compensate for the wear. Thus by suitably adjusting this screw the throw of the lever I in 85 operating the clutch may be maintained always the same.

What I claim as my invention is:

1. The combination with mechanism for controlling a clutch, of a hand-controlled 90 lever for operating said mechanism, a pedal lever adapted to operate said mechanism while connected to be operated upon the movement of said hand-controlled lever, and means of adjustment intermediate said 95 hand-controlled lever and said clutch operating mechanism for compensating for wear in the clutch and maintaining the throw of said lever the same.

2. A control mechanism for a clutch comprising a pedal lever, a hand controlled lever, a slide actuated by said hand controlled lever, a cam on said slide, a rock arm actuated by said cam, and a member actuated by 100 said rock arm having a push bearing on said pedal lever.

3. A control mechanism comprising clutch 105 operating mechanism, a pedal lever for actuating said mechanism, a hand controlled lever forming a second means for actuating 110

said mechanism, and means of adjustment intermediate said hand lever and said clutch operating mechanism for compensating for wear in the clutch and maintaining the 5 throw of said lever the same.

4. A control mechanism comprising clutch operating mechanism, a pedal lever for actuating the same, a hand controlled lever, a slide actuated thereby, a cam on said slide, a 10 rock arm actuated by said cam, a second rock arm connected to said first rock arm and an adjustable screw in said second rock arm having a bearing on said pedal lever, for the purpose described.

15 5. A control mechanism for a clutch comprising a pedal lever, a hand-controlled lever, a slide actuated longitudinally by said hand-controlled lever, a cam on said slide, a rock arm actuated by said cam, a member actuated by said rock arm having a push bearing

on said pedal lever, and means of adjustment between said member and said pedal lever.

6. A control mechanism for a clutch, comprising a rock shaft, a depending rock arm thereon, a pedal lever for operating said rock 25 arm, a second rock arm on said rock shaft, a member connecting said second rock arm with said pedal lever, a second rock shaft, a hand-controlled lever thereon, a rock arm also on said rock shaft, a slide actuated longitudinally by said rock arm, and a cam on 30 said slide for operating the second rock arm on said first rock shaft.

In testimony whereof I affix my signature in presence of two witnesses.

HOWARD E. COFFIN.
